(57) **CLAIM**

We claim the ornamental design for a display screen with transitional graphical user interface, as shown and described.

DESCRIPTION

FIG. 1 is a front view of a display screen with transitional graphical user interface showing a first image in a sequence; FIG. 2 is a second image thereof; FIG. 3 is a third image thereof; FIG. 4 is a fourth image thereof; FIG. 5 is a fifth image thereof; FIG. 6 is a sixth image thereof; FIG. 7 is a seventh image thereof; and, FIG. 8 is an eighth image thereof.

The broken line showing of a display screen with transitional graphical user interface is included for the purpose of illustrating portions of the article and forms no part of the claimed design.

The appearance of the transitional image sequentially transitions between the images shown in FIGS. 1-8. The process or period in which one image transitions to another forms no part of the claimed design.
